UNITED STATES PATENT OFFICE

FRED M. OPITZ, OF MILWAUKEE, WISCONSIN, ASSIGNOR TO HEXCEL RADIATOR COMPANY, OF MILWAUKEE, WISCONSIN, A CORPORATION OF WISCONSIN

DESIGN FOR AN AIR CONDITIONING DEVICE

Application filed October 26, 1932. Serial No. 45,583. Term of patent 7 years.

To all whom it may concern:

Be it known that I, FRED M. OPITZ, a citizen of the United States, residing at Milwaukee, in the county of Milwaukee and State of Wisconsin, have invented a new, original, and ornamental Design for an Air Conditioning Device, of which the following is a specification, reference being had to the accompanying drawing, forming a part thereof.

Figures 1 and 2 are, respectively, front and rear perspective views showing my new design.

I claim:

The ornamental design for an air conditioning device, as shown.

In witness whereof, I hereunto subscribe my name this 18th day of October, 1932.

FRED M. OPITZ.
